UNITED STATES PATENT OFFICE.

ALLEN E. OSTRANDEE, OF BRONXVILLE, NEW YORK, ASSIGNOR TO AMERICAN CAR AND FOUNDRY COMPANY, OF NEW YORK, N. Y., A CORPORATION OF NEW JERSEY.

SWIVEL MINE-CAR-HITCHING DEVICE.

Application filed December 6, 1924. Serial No. 754,312.

The following is a full, clear and exact description, such as will enable others skilled in the art to which it appertains to make and to use the same, reference being had to the accompanying drawings which illustrate the preferred form of the invention; though it is to be understood that the invention is not limited to the exact details of construction shown and described, as it is obvious that various modifications thereof within the scope of the claims will occur to persons skilled in the art.

In said drawings:

Figure 1 is a plan view showing fragments of adjacent end portions of mining cars connected by the improved hitching device;

Figure 2 is an enlarged view of the improved hitching device, the device being shown principally in top plan and partially in longitudinal section;

Figure 3 is a side elevation of the improved hitching device, one of the car engaging links being partially broken away;

Figure 4 is a transverse sectional view taken along the line 4—4 of Figure 2;

Figure 5 is a transverse sectional view through the improved swivel pin which connects the car engaging links, the view being taken along the line 5—5 of Figure 2;

Figure 6 is a fragmentary view partially in top plan and partially in longitudinal section and showing a modified form of swivel pin;

Figure 7 is a view similar to Figure 6 showing another modified form of swivel pin, and

Figure 8 is a view similar to Figures 6 and 7 and showing a further modified form of swivel pin.

An object of this invention is to provide an improved mine car hitch which may be used for connecting mine cars and will be provided with car engaging links having a special construction at their adjacent ends and connected by a swivel pin which is of an improved construction and will permit the swivel to have rotary movement in the cross heads at adjacent ends of the links and further permit the links to have longitudinal movement upon the swivel pin without danger of the pin being broken.

Another object of the invention is to so construct the swivel pin that side sections forming the same may be securely held in spaced relation to each other by a separa-

ting wedge and this wedge securely held in place and prevented from moving longitudinally out of place between the sections of the pin.

This hitching device is for use in connecting mine cars which are of a conventional construction and are indicated in general by the numeral 10. Each car is provided with the usual draw bar 11 through which passes a pin 12 so that the hitching device 65 may be connected with the cars by these pins. This hitching device is provided with links 13 which are substantially U-shaped but are provided at their adjacent ends with cross heads 14 in which are formed openings 15. These openings 15 taper inwardly, as shown in Fig. 2, so that the links may have tilting movement upon the swivel pin 16 without danger of the pin being bent or broken or the cross heads broken.

The swivel pin may be formed as shown in Fig. 2 or as shown in Figs. 6, 7 or 8. These various forms are very similar to each other but are somewhat different in their details of construction. The form 80 shown in Fig. 2 will first be described. Referring to Fig. 2, it will be seen that the swivel pin is provided with longitudinally extending side sections 17 which are provided at their ends with enlarged head 85 forming extensions 18. These sections 17 when placed in contact with each other do not form a perfect circle but when spread apart by the wedge 19, as shown in Fig. 5, these sections will have their arcuate side 90 faces constitute arcs of an interrupted circle which will be approximately of a diameter corresponding to the diameter of one of the openings 15 at its inner end. The head forming side extensions or flanges 18 of 95 these sections 17 are of greater sectional area than the intermediate sections 17 but when placed in contact with each other before insertion of the wedge these head forming portions or flanges will provide a circular head having a diameter small enough to permit of its being passed through the openings 15. It will thus be seen that before the wedge is put in place the sections forming the swivel can be placed in contact with each other and pass through the openings 15 in the cross head 14 of the links 13.

The wedge will then be put in place as shown and in the form shown in Fig. 2 this wedge will be secured against moving lon- 105

5 gitudinally out of place by means of a rivet 20 which passes through ears 21 extending from the sections 17 at one end of the swivel and through a longitudinally extending slot 22 provided in the wedge. By having this rivet passing through a slot 22 the wedge and the sections 17 of the swivel pin may

10 be permitted to have a slight longitudinal movement relative to each other without danger of the rivet being sheared off. It will therefore be seen that this hitching device is so formed that the swivel pin may be easily put in place and the wedge secured so that the links are connected by a swivel 15 which will permit of rotary and tilting movement of the links. It should be further noted that the swivel is of such length that the links will be permitted a slight movement longitudinally of the swivel but the 20 will contact with each other before the ends of the swivel can strike the outer ends of the links. Therefore the swivel will not receive end blows which might tend to break it.

25 In the form shown in Fig. 6, the side sections 17 which form the swivel pin are of the same construction as those shown in Fig. 2 except that the ears 21 have been omitted. In this form the key or wedge 23 which takes 30 the place of the wedge 19 is of greater length than the wedge 19. This wedge 23 has one end portion bent to provide an offset abutment head 24 which will limit movement of the wedge between the sections of the swivel and further permit the wedge to be easily 35 driven into place with a hammer if it does not pass readily between the swivel pin forming sections. After the wedge has been put in place the other end portion of this wedge will be bent over from the position indicated 40 by dotted lines to the position shown in full lines and provide an abutment head 25 which co-operates with the head 24. This wedge will therefore be securely held against longitudinal movement in either direction and 45 can not slip out of place.

50 In Fig. 7, the wedge 26 is a short wedge which will be forced into place between the sections 17 forming the swivel pin. These sections 17 are provided at their ends with 55 tongues 27 which normally extend longitudinally of the swivel as indicated by dotted lines so that the wedge can be easily put in place. After the wedge has been put in place the tongues will be bent over as shown in 60 full lines and will be disposed in overhanging relation to the ends of the wedge. The wedge will therefore be prevented from moving longitudinally out of place between the swivel forming sections.

65 In Fig. 8, the construction is very similar to that shown in Fig. 2, the only difference between the form shown in this figure and that shown in Fig. 2 is that only one of the swivel forming sections has been provided with an arm or tongue extension 28 which

takes the place of the arms 21 and the wedge 29 is secured by a rivet 30 which passes through the arm 28 and extended end portion of the wedge without the wedge being provided with an opening of sufficient size to 70 permit longitudinal sliding of the wedge.

What is claimed is:

1. A coupling of the character described comprising links disposed in end to end relation to each other and having adjacent ends 75 provided with cross heads having aligned openings, a swivel pin extending through the openings in the cross heads of said links and having its end portions provided with heads for preventing withdrawal of the swivel, so said swivel pin being split longitudinally to provide side sections movable towards and away from each other, and a wedge between the sections holding them spaced apart, the wedge being held against movement from 80 between the sections.

2. A swivel comprising longitudinally extending side sections having co-operating head portions at their ends shaped for passing through an opening when the sections 90 are in contact and for retaining the swivel in the opening when the sections are spaced from each other, and a wedge positioned between the sections and having its end portions bent to engage the heads and hold the 95 wedge against longitudinal movement out of place.

3. A coupling of the character described comprising a plurality of links disposed in end to end relation to each other each link 100 having a perforated cross head and a swivel provided with retaining ends for loosely connecting said links, said swivel extending through the openings of the cross heads to slidably and rotatably connect the links and 105 being of a length slightly greater than the combined thickness of the two cross heads.

4. A coupling of the character described comprising links disposed in end to end relation to each other and each link having an 110 end portion comprising a perforated cross head and a swivel pin extending through said openings and having retaining heads at its ends adapted to contact with said cross heads to prevent withdrawal, said swivel between the retaining heads being of slightly 115 greater length than the combined thickness of the two cross heads.

5. In a mine car hitching, a plurality of unbroken links each adapted to engage a 120 coupling pin, said links having perforated cross heads, a headed two-part swivel pin extending through perforations in said cross heads and means spacing the parts of said pin when in said perforations, said means being held against longitudinal movement relative to the swivel pin.

In witness whereof I have hereunto set my hand.

ALLEN E. OSTRANDER.
